UNITED STATES PATENT OFFICE.

WILLIAM R. BANKSON, OF PITTSBURGH, PENNSYLVANIA.

MAIL BOX.

Application filed August 23, 1927. Serial No. 214,895.

My invention relates to certain new and useful improvements in mail boxes and the primary object thereof is to provide a mail box of the character described which will uniformly stack letter mail with the addressed side of the latter generally turned in the same direction; under such conditions greatly facilitating and expediting the handling, assorting, and the postage cancellation of letter mail.

Further objects of the invention are to provide a device of the type stated which is simple in its construction and arrangement, strong, durable and efficient in its use, positive in its action, compact, and comparatively inexpensive to manufacture.

With the foregoing and other objects in view which will appear as the description proceeds, the invention resides in the combination and arrangement of parts and in the details of construction hereinafter referred to, it being understood that changes in the precise embodiment of the invention can be made within the scope of what is claimed without departing from the spirit of the invention.

In the drawing wherein like numerals of reference designate corresponding parts throughout the several views:—

Figure 1 is a side elevational view of a mail box constructed in accordance with the invention, and with portions thereof in cross section.

Figure 2 is a sectional view on line II—II, Fig. 1.

Referring in detail to the drawing 1 denotes a frame structure including a mail receptacle 2 and a gear casing 3. The mail receptacle 2 provides a mail chamber 4, which is adapted for the reception of letter mail only. The mail receptacle 2 is semi-circular in contour, and is rectangular in transverse cross section, and the mail chamber 4 is consequently of like configuration.

The mail receptacle 2 is disposed rearwardly and the inner wall 5 thereof is formed with a centrally arranged slot 6, which extends throughout the length of the latter.

A flat carrier plate 7 is arranged in the chamber 4 and is fixed to the outer end of a radial arm 8, which extends through the slot 6 and has its inner end formed to provide a hub 9. The latter is formed with reduced ends 10 and 11, which are journaled for rotation in respective bearings 12 and 13. The latter are fixed to the frame structure 1 at

points thereof providing a pivotal connection, which is disposed at the axial center of the semi-circular receptacle 2.

The carrier plate 7 is rectangular in shape to conform to the transverse contour of the chamber 4 in which it is arranged. The carrier plate 7 is positioned to extend transversely through the chamber 4, and the movement of the arm 8 on its pivotal connection in the bearings 12 and 13 will permit of the free passage of the carrier plate 7 through the chamber 4 from the top to the lower end thereof. The upper end of the slot 6 limits the upward movement of the arm 8, so that when the latter is in its maximum upward position, the plate 7 will be inclined rearwardly from its lower to its upper end, as clearly shown in dash lines in Figure 1.

A coil spring 14, having one end fixed to the frame structure 1 and the other end thereof to the hub 9, surrounds the latter, and normally functions to force the arm 8 and the plate 7 to their maximum upward position.

A gear 15 is fixed to one end of the hub 9 and meshes with a pinion 16, which is fixed on a shaft 17. The latter is suitably journaled for rotation in the frame structure 1 and also carries a fixed gear 18. The gear 18 meshes with a pinion 19, which is fixed on a shaft 20. The latter is suitably journaled for rotation in the frame structure 1, and also carries the ratchet wheel 21 fixed thereto.

A substantially U-shaped saddle 22 straddles the top portion of the receptacle 2. One leg 23, of the saddle 22, has its lower end pivotally mounted on the shaft 20, and the other saddle leg 24 has its lower end pivotally connected to a pivoting pin 25, which is fixed in the frame structure 1. The pin 25 and shaft 20 are horizontally aligned relatively to each other.

The rear wall 26 is formed with a transversely extending slot 27, which is disposed at the top of the former and provides an opening for the insertion of the letters into the chamber 4. The top of the saddle 22 normally serves as a closure for the letter slot 27, but the pivotal connection of the saddle 22 on the pin 25 and shaft 20 allows the saddle 22 to be manually shifted to the rearward direction to clear the letter slot 27 and permit of the insertion of letter mail through the latter. A spring 28, connected with the saddle 22 and with the frame structure 1, normally acts to force the saddle 22 to the closing position to cover the letter slot 27.

A rearwardly disposed actuating pawl 29 is pivotally connected, as at 30, to the inner side of the saddle leg 23 and engages the top of the ratchet wheel 21. Each time that the 5 saddle 22 is shifted rearwardly, the engagement of the pawl 29 on the ratchet wheel 29 will cause the partial rotation of the latter in the clockwise direction. Owing to the geared connection of the ratchet wheel 29, with the 10 hub 9, the arm 8, will also be actuated to shift the carrier plate 7 in the clockwise direction in the chamber 4, thereby providing space in the latter for the following letter, each time the saddle 22 is shifted rearwardly in the 15 manner stated. The first letter that is deposited in the chamber 4 will position itself flatly against the carrier plate 7, and each subsequent letter deposits itself against the last letter deposited. The distance of travel of 20 the carrier plate 7 by each operation of the saddle 22 is predetermined and approximately commensurate to the mean thickness of ordinary letters.

To prevent the return of the plate 7 in the 25 chamber 4 by the action of the spring 14, while the spring 28 is returning the saddle 22 to the normal or closing position, a locking pawl 31 is provided. The latter is pivotally connected to the frame structure 1 and engages the 30 ratchet wheel 21 forwardly of the actuating pawl 29.

The pawl 29 is formed with a forwardly projecting forked end 32, and the pawl 31 is likewise formed with a similar forwardly 35 projecting forked end 33, which is disposed parallel to and below the forked end 32 of the pawl 29.

A vertically disposed releasing rod 34 is 40 slidably connected to the frame structure 1, and extends through the forked ends 32 and 33 of respective pawls 29 and 31. The upper end of the releasing rod 34 is threaded and carries a pair of adjusting nuts, respectively indicated at 35 and 36. The nut 35 is seated 45 on the top of the forked pawl end 32, and the nut 36 is seated on the top of the forked pawl end 33. Coil springs 37 and 38 are mounted on rod 34 directly beneath respective forked pawl ends 32 and 33. The lower ends of the 50 springs 37 and 38 seat on pins 39 which extend transversely through rod 34, while the upper ends thereof tensionally engage the lower side of respective pawl ends 32 and 33. The action of the springs 38 and 39 serve to maintain 55 the operative engagement of the pawls 29 and 31 with the ratchet wheel 21, while permitting of the rotation of the latter in the clockwise direction.

The lower end of the releasing rod 34 is 60 pivotally connected to one arm of a bell crank 40. The latter is pivotally mounted to the frame structure 1. The other arm of the bell crank 40 is pivotally connected with a horizontally disposed connecting rod 41, which 65 has its rear end pivotally connected, as at 42,

adjacent to the upper end of the receptacle door 43.

The door 43 covering the outlet for removing the letter mail from the receptacle 2, is disposed at the lower end of the receptacle 70 rear wall 26, and is hingedly connected, as at 44, at its upper end to open outwardly rearward. The lower end of the door 43 is provided with suitable latching or locking elements 45 for maintaining the door in the 75 closed position.

It will be noted that the connecting rod connection 42 is disposed below the hinged door connection 44, whereby the opening movement of the door 43 will draw the releasing rod 34 downwardly and shift the pawls 29 and 31 from their engagement with the ratchet wheel 21. When the mail has been removed from the receptacle 2, and the pawls 29 and 31 are disengaged from the ratchet 80 wheel 21 by the opening movement of the door 43, the action of the spring 14 will return the carrier plate 7 to its upward position. When the door 43 is closed the pawls 29 and 31 again engage the ratchet wheel 31 to 85 respectively actuate and lock the latter in the manner herein stated.

In the event that the mail is being gathered from my improved device before the chamber 4 has been filled with sufficient mail to bring 90 the carrier plate 7 below the upper end of the door 23, it will be necessary to manually turn the hub 9 a distance to bring the plate 7 and letter mail thereon below the upper end of the door 43, to permit of the removal of the 95 mail matter. For this purpose a squared socket 46 is formed in the reduced end 10 of the hub 9. The socket 46 is adapted for the reception of a suitable implement for rotating the hub 9 and the parts associated therewith. 100

The rearward movement of the saddle 22, by the mail depositor, is limited by a fixed stop pin 47, and the return or forward movement of the saddle 22, by the action of the spring 28, is limited by a stop lug 48 mounted 110 on the forward end of the rear wall 26. It is only necessary to shift the saddle 22 a distance sufficient to clear the slot 27 to permit of the insertion of letter mail, and to again close the slot 27 after such deposit has been 115 made.

All letters inserted in my improved mail box will be neatly stacked against each other, and as the depositor usually takes a last look 120 at his letter to satisfy himself that the same is properly stamped and addressed, the letters will be found to be generally turned in the same direction, thereby facilitating the handling of the mail matter when same reaches the post office.

What I claim is:

1. In a mail box of the character described, a mail receptacle provided with a mail inlet opening, a shiftable closure member for said mail inlet opening and normally closing the 130

- latter, a carrier plate mounted in said receptacle, and means actuated by the movement of said closure member for shifting said carrier plate to a predetermined position in said receptacle.
2. In a mail box of the character described, a mail receptacle provided with a mail inlet opening, a shiftable closure member for said mail inlet opening and normally closing the latter, a carrier plate mounted in said receptacle, means actuated by the movement of said closure member for shifting said carrier plate to a predetermined position in said receptacle, and means for returning said closure member to its normal closing position.
3. In a mail box of the character described, a mail receptacle provided with a mail inlet opening, a shiftable closure member for said mail inlet opening and normally closing the latter, a carrier plate mounted in said receptacle, means actuated by the movement of the closure member to the opening position for shifting said carrier plate to a predetermined position in said receptacle.
4. In a mail box of the character described, a mail receptacle provided with a mail inlet opening, a shiftable closure member for said mail inlet opening and normally closing the latter, a carrier plate mounted in said receptacle, means actuated by the movement of the closure member to the opening position for shifting said carrier plate to a predetermined position in said receptacle, and spring actuated means for returning said closure member to its normal closing position.
5. In a mail box of the character described, a receptacle providing a mail chamber, said receptacle being semi-circular in contour and having a mail inlet slot formed in the top thereof, a closure member normally closing said slot, a flat carrier plate extending transversely through said chamber and normally disposed in the upper end of the latter, an arm supporting said carrier plate and having its inner end pivotally connected at the axial center of said circular receptacle, gear elements connecting said closure member with the said arm, the movement of said closure member to the opening position actuating said gear element to shift said carrier plate to a predetermined position in said chamber.
6. In a mail box of the character described, a receptacle providing a mail chamber, said receptacle being semi-circular in contour and having a mail inlet slot formed in the top thereof, a closure member normally closing said slot, a flat carrier plate extending transversely through said chamber and normally disposed in the upper end of the latter, an arm supporting said carrier plate and having its inner end pivotally connected at the axial center of said circular receptacle, gear elements connecting said closure member with the said arm, the movement of said closure member to the opening position actuating said gear element to shift said carrier plate to a predetermined position in said chamber, and spring actuated means for returning said closure member to its normal closing position.
7. In a mail box of the character described, a receptacle providing a mail chamber, said receptacle being semi-circular in contour and having a mail inlet slot formed in the top thereof, a closure member normally closing said slot, a flat carrier plate extending transversely through said chamber, and normally disposed in the upper end of the latter, an arm supporting said carrier plate and having its inner end pivotally connected at the axial center of said circular receptacle, gear elements connecting said closure member with the said arm, the movement of said closure member to the opening position actuating said gear element to shift said carrier plate to a predetermined position in said chamber, spring actuated means for returning said closure member to its normal closing position, and spring actuated means for returning said carrier plate to its normal upward position.
- In testimony whereof I affix my signature.
- WILLIAM R. BANKSON.
